[21] Appl. No.: **815,961**[57] **CLAIM**

The ornamental design for an oil drip pan for rebuilding engines, as shown and described.

DESCRIPTION[22] Filed: **Jan. 2, 1992**

FIG. 1 is a perspective view of the oil drip pan for rebuilding engines showing our new design;
FIG. 2 is a front elevational view thereof;
FIG. 3 is a side elevational view thereof and the opposite side is a mirror image thereof;
FIG. 4 is a top plan view thereof;
FIG. 5 is a bottom plan view thereof; and,
FIG. 6 is a rear elevational view thereof.
